UNITED STATES PATENT OFFICE.

WILLIAM N. BALLARD, OF KANSAS CITY, KANSAS, ASSIGNOR OF ONE-FOURTH TO
JAMES S. CUMMINS, OF KANSAS CITY, KANSAS.

AUTOMATIC FIRE-ALARM SYSTEM.

1,242,312.

Specification of Letters Patent.

Patented Oct. 9, 1917.

Application filed July 12, 1916. Serial No. 108,852.

To all whom it may concern:

Be it known that I, WILLIAM N. BALLARD, a citizen of the United States, residing at Kansas City, in the county of Wyandotte and State of Kansas, have invented certain new and useful Improvements in Automatic Fire-Alarm Systems, of which the following is a specification.

My invention relates to automatic fire alarm systems wherein the rooms of a building are protected with a net work of cables held under tension and adapted to part and sound an alarm, when subjected to a predetermined temperature.

One object of my invention is to provide an efficient alarm system of inexpensive construction, so that it may be installed not only in large buildings, but also in cottages and small business houses where the cost of other systems is prohibitive.

A further object is to provide an alarm system free of the objections incident to sprinkler systems, such as high cost of installation, liability to freezing and corrosive troubles, damaging goods by wetting the same, etc.

Other objects of the invention will herein-after appear, and in order that said invention may be fully understood, reference will now be made to the accompanying drawings, in which;

Figure 1 is a vertical sectional perspective view showing two stories of a building equipped with the invention.

Fig. 2 is a detail front elevation of a weight and adjacent parts employed in carrying out the invention.

Fig. 3 is a vertical section through line III of Fig. 2.

Fig. 4 is a plan view of a twin sheave block employed in carrying out the invention.

Fig. 5 is a horizontal sectional view of a building with one of the rooms thereof equipped with a modified arrangement of cables.

Fig. 6 is a modified form of means for taking up slack in the cables.

A, designates a building having upper and lower rooms B and C, respectively.

1 designates a series of cables all but the initial one of which are fixed at their ends to the ceilings of the rooms B and C by any suitable means, screw eyes 2 being shown

for that purpose. Each cable 1 is bent at 55 an angle of ninety degrees at one or more points intermediate its ends, and said bent portions are connected to the bent portions of the adjacent cables by suitable means, such as rings 3. The cables 1 are prevented 60 from sagging unduly intermediate their ends by screw eyes 4, secured to the respective ceilings of the rooms B and C.

The initial cable 1 is secured at one end to a screw eye 2 and at its opposite end to a 65 block 5 containing a sheave 6, around which a long cable 7 is bent. The long cable 7 is attached at its upper end to a screw eye 8 and passing downward around the sheave 6, and a sheave 9, extends through a tube 10 70 to the lower floor C, where it bends around a sheave in each of the twin sheave blocks 11 and is attached to a screw eye 2 secured in the ceiling of the room C. The arrangement of the cables 1 in the lower room C is 75 the same as that in the upper room B. The sheave 9 is mounted in a block 12, secured to the adjacent wall of the room B.

13 designates a main cable for holding all of the aforementioned cables under tension. 80 The upper portion of the main cable 13 runs around a sheave of one of the blocks 11 and is attached to a screw eye 14 projecting from the adjacent wall of the room C. The lower end of the cable 13 is attached to a weight 85 15, which is heavy enough to hold all of the cables taut.

The weight 15 extends loosely into a cup 16 above the bottom of which it is normally suspended by the main cable 13. The bottom of the cup 16 is provided with a suitable cushion 17 to relieve the shock incident to the dropping of the weight 15 should any of the cables part.

18 designates a switch for closing an electric circuit 19. Said switch 18 consists of a blade 20, projecting from the weight 15, and two spring contacts 21 secured to the tube 16 but insulated therefrom. Each contact 21 is connected to a terminal of the circuit 19, which latter embodies gongs 22 and 23, one of which is located within the building to notify the occupants thereof when a fire occurs in any part of said building, the other being located outside of the building 105 to notify people passing by. The circuit 19 is, also, preferably, extended to the nearest fire station to sound an alarm therein.

Each of the cables 1, consists preferably, of a fine wire united at intervals by fuses 25, arranged to part at a predetermined temperature and allow the weight 15 to drop and close the circuit 19, or said cables may be made in short lengths united by fusible solder, or they may consist of inflammable material, such as ordinary cords, the main object being to have them part when subjected to fire and allow the weight 15 to drop and close the circuit 19.

By attaching the upper end of the cable 7 to the screw eye 8 and running it over the sheave 6 at an angle of ninety degrees and 15 over the sheave 9 at an angle of forty-five degrees, seven and one-half pounds exerted on said cable 7 exerts a ten pound pull on the initial cable 1 attached to the block 5, and by bending each cable 1 at an angle of 29 ninety degrees between its ends and connecting it to a bend of the adjacent cable by a ring 3, a ten pound pull is exerted on each of said cables 1.

By bending the main cable 13 at an angle 25 of ninety degrees around its respective sheave in one of the blocks 11, approximately the same tension exerted thereon by the weight 15 is transmitted to each of the cables 1 on the floor C. In other words, 30 if seven and one-half pounds is exerted on said main cable 13, approximately seven and one-half pounds will be exerted on each cable 1. If it is desired to increase the tension on the lower cables 1, the upper portion 35 of the cable 13 is bent over two sheaves, as in the case of the upper portion of the cable 7, whereupon a seven and one-half pound weight on said cable 13 will exert approximately ten pounds on each cable 1, 40 on the floor C.

Compounding of the tension on the cables 1 may be further increased by the arrangement disclosed at the right side of Fig. 4, which will hereinafter be referred to.

Referring again to Fig. 1, the operation 45 is substantially as follows: Should a cable 1 on either of the floors B and C part, it will permit all of the cables 1 on its respective floor to relax, whereupon the weight 15 immediately drops and closes the circuit 18.

If desired sheave blocks 11 may be substituted for the rings 3, to reduce the friction incident to the movement of the slackened cables in said rings 3.

Referring again to the modified form, Fig. 5, two rooms D and E are shown on the same floor of the building A', separated by a partition F to show how my system of wiring can be carried throughout various 60 parts of the building. The arrangement of the cables 1 in the room D is the same as disclosed in room C of Fig. 1, but in room E the cables 1 instead of extending clear across the room, extend only part way across 65 and those on one side of the room are ar-

ranged in staggered relation to those at the opposite side of said room. Also instead of having ninety degree bends, as in the case of each cable 1, the cables 1^a are straight throughout their length, one end of each 70 being attached to a screw eye 2^a, while the opposite end is attached to a ring 3^a. A long cable 27 is rove zigzag through the rings 3^a and attached at one end to a ring 3^a and at its opposite end to a screw eye 28.

A long cable 29 is attached at one end to a screw eye 30, and after bending at, approximately, ninety degrees around a ring 3^a extends from the room E into the room D through a tube 10^a in the partition F, 80 and on bending over the sheaves in two twin sheave blocks 11 at angles of ninety degrees, is secured to the ceiling of said room D by a screw eye 2.

By bending the cable 29 at approximately, 85 ninety degrees adjacent the screw eyes 30, and extending the cable 27 at an angle of forty-five degrees from said ninety degree angle and bending it in a series of ninety degree angles where it is connected to the 90 short cables 1^a, seven and one-half pounds exerted on the cable 29, exerts ten pounds on cable 27, which in turn exerts twelve and one-half pounds on each cable 1^a. Thus while the wires in room D control the tension of the wires in room E, the latter wires are under greater tension than the former.

The cables 1 in the room D are held under tension by a long cable 7^a, extending through a twin sheave block 11^a, and in turn is held under tension by a main cable 13^a extending through the twin sheave block 11^a and attached at its upper end to a screw eye 14^a. The lower end of the main cable 13^a may be weighted as in the case of cable 13.

Owing to the arrangement of the cables on the various floors and the line of cables 7 and 13 leading down to the weight 15, said weight controls the cables on each floor independently of the cables on the other floors, 110 hence when a cable on one floor parts the cables on said floor relax and allow the weight to drop and sound the alarm without causing the wires on the other floors to slacken.

If desired a spring 15^a may be substituted for the weight 15, although I consider the latter more reliable than the former.

While I have shown the cables arranged in more or less symmetrical form, it is obvious that they may be extended around stairways, elevator hatchways, etc., without impairing the efficiency of my system. Such other changes may also be made as properly fall within the spirit and scope of the claims.

Having thus described my invention, what I claim and desire by Letters Patent, is:—

1. In an automatic alarm, a series of cables arranged at angles of ninety degrees intermediate their ends, means for securing

- all but one of said ends to the ceiling of a building, means connecting the adjacent angles of said cables, a block to which the free end of the initial cable is attached, a 5 cable attached at its upper end to the ceiling and bent at an angle of ninety degrees over said block, a second block arranged below the first block and over which the last-mentioned cable is bent at an angle of ninety 10 degrees, means operably connected to the last cable to hold it and the first-mentioned cables, under tension, and a circuit closer which is closed by said means should any of the cables become slack.
- 15 2. In an automatic alarm, a series of cables arranged at angles of ninety degrees intermediate their ends, means for securing said ends to the ceiling of a building, rings connecting the adjacent angles of said cables, a main cable fixed at its upper end and bent adjacent said end at an angle of ninety degrees, means operably-connecting said main cable at its angle to the series of cables, a weight connected to the lower 20 end of said main cable, and a circuit closer controlled by said weight.
- 25 3. In an automatic alarm, a system of cables arranged at angles in the stories of a building adjacent the ceilings thereof, a long cable in each upper story connected to the system therein and leading to the system in the story below to normally retain said systems under tension, a main cable operably-connected to the lowest of said long cables 30 to retain the long cables under tension, means for retaining said main cable under tension, and a circuit closer controlled by said means.
- 35 4. In an automatic alarm, a system of cables arranged in the stories of a building adjacent the ceilings thereof, a long cable in each upper story connected to the system therein and leading to the system in the story below to normally retain said systems 40 under tension, a main cable fixed at its upper end and bent near said end at an angle, means operably-connecting said main cable at its angle to the lowermost long cable, means for retaining said main cable under 45 tension, and a circuit closer controlled by 50
- said means, said circuit closer closing an alarm circuit.
5. In an automatic alarm, a system of cables in the different stories of a building adjacent the ceilings thereof, a long cable in each upper story bent at angles and connected to the system therein and leading to the system in the story below to normally retain said systems under tension, means to which the ends of each long cable are fixed, 55 a main cable operably-connected to the lowest of said long cables to retain the long cables under tension, a weight for retaining said main cable under tension, and a circuit closer controlled by said weight, said circuit 60 closer closing an alarm circuit.
6. In an automatic alarm, a series of cables in the different stories of a building arranged at angles intermediate their ends, a long cable in each upper story connected 65 to the series of cables therein and leading to the series of cables in the story below, fusible means embodied in said cables, means for securing the ends of the cables to the ceiling of a building, means connecting the 70 adjacent angles of said cables, a main cable fixed at its upper end and operably-connected to the lowest of the long cables, means for holding said main cable under tension, and a circuit closer controlled by said means. 75
7. In an automatic alarm, a series of cables arranged at angles intermediate their ends, eyes projecting from the ceilings of a building and to which the ends of the cables are fixed, fusible means embodied in said 80 cables, means connecting the adjacent angles of said cables, a main cable fixed at its upper end and bent adjacent said end at an angle, a twin sheave block operably-connecting said main cable at its angle to an angle 85 of the series of cables, a weight connected to the lower end of said main cable, and a circuit closer controlled by said weight.

In testimony whereof I affix my signature,
in the presence of two witnesses.
